(57) **CLAIM**

The ornamental design for a closure cap, as shown and described.

DESCRIPTION

This application is related by subject matter to co-pending application Ser. Nos. 29/382,735, filed Jan. 6, 2011, 29/382,739, filed Jan. 6, 2011, 29/382,732, filed Jan. 6, 2011, and 29/382,744, filed Jan. 6, 2011, each entitled "Closure Cap." FIG. 1 is a top plan view of a closure cap according to my design;

FIG. 2 is a perspective view thereof;

FIG. 3 is a side view thereof, from the perspective of Arrow 3 shown in FIG. 1;

FIG. 4 is a side view thereof, from the perspective of Arrow 4 shown in FIG. 1;

FIG. 5 is an enlarged, partial cross-sectional view of a portion thereof, taken in the direction of line 5 shown in FIG. 1; and,

FIG. 6 is an enlarged, partial cross-sectional view of a portion thereof, taken in the direction of line 6 shown in FIG. 1.

The bottom plan view and intermittent sides views of this claimed design are apparent from FIGS. 1-6. Any broken line portion of the drawings is included to show environmental subject matter only and forms no part of the claimed design.
